[57] CLAIM

The ornamental design for a bow clasp, as shown and described.

DESCRIPTION

FIG. 1 is a rear elevational view of a bow clasp showing my new design holding a bow;

FIG. 2 is a rear elevational view;

FIG. 3 is a front elevational view;

FIG. 4 is a right side elevational view;

FIG. 5 is a left side elevational view;

FIG. 6 is a top plan view, the opposite side being identical;

FIG. 7 is a front elevational view of a bow clasp showing a modified form of my new design;

FIG. 8 is a rear elevational view thereof;

FIG. 9 is a right side elevational view thereof;

FIG. 10 is a left side elevational view thereof; and

FIG. 11 is a top plan view, the opposite side being identical.

The broken line showing of a bow in FIG. 1 is for illustrative purposes only and form no part of the claimed design.
